SCOOP FOR CLEANING SANITARY CAT BOXES

Henry E. Lowe, Jr., N. Edward St.,
Cassopolis, Mich. 49031

Filed Sept. 14, 1972, Ser. No. 288,917

Term of patent 14 years

Int. Cl. D30—99

U.S. Cl. D30—99

Fig. 1

Fig. 2

FIG. 1 is a plan view of a scoop for cleaning sanitary cat boxes embodying the present invention, showing it in its unfolded position;

FIG. 2 is a perspective view of the scoop for cleaning cat boxes of FIG. 1, showing it in its folded position;

FIG. 3 is a bottom view of the scoop for cleaning sanitary cat boxes, shown in its folded condition.

I claim:

The ornamental design for a scoop for cleaning sanitary cat boxes, substantially as shown.
